DESIGN FOR A RETRACTABLE SIGN

John J. Hammer, Detroit, Mich.

Application April 12, 1946, Serial No. 128,551

Term of patent 7 years

(Cl. D1—12)

To all whom it may concern:

Be it known that I, John J. Hammer, a citizen of the United States, residing at Detroit, in the county of Wayne and State of Michigan, have invented a new, original, and ornamental Design for a Retractable Sign, of which the following is a specification, reference being had to the accompanying drawing, forming a part thereof, in which:

Fig. 1 is a perspective view of a retractable sign with the side panels thereof disposed in their depending position, showing my new design.

Fig. 2 is a side elevational view thereof.

Fig. 3 is a side elevational view thereof with the side panels disposed in their retracted position.

Fig. 4 is a bottom view with the side panels disposed in their depending position, and

Fig. 5 is a bottom view showing the side panels disposed in their retracted position.

The essential features of my design reside in the portion shown in full lines.

I claim:

The ornamental design for a retractable sign, substantially as shown and described.

JOHN J. HAMMER.
